UNITED STATES PATENT OFFICE

SIEVERT THEODORE ANDERSON, OF CHICAGO, ILLINOIS

TROUSERS

Application filed July 8, 1929. Serial No. 376,731.

The invention relates to improvements in trousers, especially adapted for use by hunters, fishermen and for other outdoor sports, the object of the invention being to provide an improved construction for the lower leg portions of said trousers.

Another object of the invention is the provision of an improved knee-guard construction for said trousers.

Other objects will appear hereinafter.

The invention consists in the combinations and arrangements of parts hereinafter described and claimed.

The invention will be best understood by reference to the accompanying drawings forming a part of this specification, and in which,

Fig. 1 is a perspective view of a pair of trousers embodying the invention,

Fig. 2 a fragmentary side view of the lower leg portion thereof,

Fig. 3 a perspective view of an elastic cuff portion employed at the lower ends of the leg portions thereof, and

Fig. 4 a view showing a modified form of construction.

The embodiment of the invention illustrated in the drawings comprises knee length trousers of any usual or desired upper portion and having the usual leg portions 5.

At their lower ends, the leg portions 5 are provided with cuff members 6 of elastic material, adapted and arranged to encompass the legs of the wearer just below the knee. Each 35 of the leg portions is also provided with a guard 7 of the same material as the leg portions 5. These guards are of a size and shape to entirely encompass the cuff portions 6 at their upper ends, being attached by stitching 8. The guard 7, tapers thence forwardly and

downwardly, being attached by stitching 9 at the extreme lower front portions of the cuff members 6, the inclined side edges 10 being free from said cuff portions. By this arrangement, elastic cuff members are provided

for the lower ends of the leg members of the trousers which perform their usual function and at the same time guards 7 are provided for the protection of said cuff members. By providing the knee-guards in the form indicated, the full elasticity of the cuffs is realized, and at the same time the cuffs are protected and guarded by the guards.

In Fig. 4 I have illustrated a modified form of construction in which the guard 7' is somewhat larger and extends beyond the side seams of the leg portions 5. A triangular-shaped insert or gore 6' of elastic material is inserted in the rear of said knee portion with its apex upwardly and its base coincided with the base of the knee-guard. The insert or gore 6' is stitched along the seam 10' to the rear edges of the knee-guard. This arrangement furnishes a somewhat cheaper construction for providing the knee-guard and holding it in place. The arrangement of the triangular insert or gore 6', as indicated, furnishes full elasticity at the bottom of the knee-guard to hold the knee-guard down and in place, and at the same time provides a knee-guard which extends substantially entirely around the knee at its top.

While I have illustrated and described the preferred form of construction for carrying my invention into effect, this is capable of variation and modification without departing from the spirit of the invention. I therefore do not wish to be limited to the precise details disclosed, but desire to avail myself of such variations and modifications as fall within the scope of the appended claims.

Having thus fully described my invention, what I claim as new and desire to secure by Letters Patent is:

1. Trousers comprising leg members; elastic cuffs at the lower ends of said leg members to encompass the legs; and guards extending from said leg members downwardly over the forward sides of said cuffs, said

guards being attached at their top and bottom edges but free at their sides.

2. Trousers comprising leg members; elastic cuffs at the lower ends of said leg members to encompass the legs; and guards extending from said leg members downwardly over the forward sides of said cuffs, said guards encompassing said cuffs at their tops but tapering forwardly and downwardly to encompass only a small portion of said cuffs at their lower front edges and being attached at their top and bottom edges but free at their sides.

In witness whereof, I have hereunto set
my hand this 20th day of June, 1929.

S. THEODORE ANDERSON.
